UNITED STATES PATENT OFFICE.

VICTOR L. COX, OF MOUNT STERLING, OHIO.

CORE.

1,371,775.

Specification of Letters Patent. Patented Mar. 15, 1921.

Application filed September 18, 1919. Serial No. 324,351.

To all whom it may concern:

Be it known that I, VICTOR L. COX, a citizen of the United States, residing at Mount Sterling, in the county of Madison and State 5 of Ohio, have invented new and useful Improvements in Cores, of which the following is a specification.

This invention relates to improvements in cores for the manufacture of the outer casings of double tube pneumatic tires.

The object of the invention is to provide a core of the above named class formed of a plurality of separable sections adapted to abut in the form of an annulus whereby the 15 various sections may be severably removed inwardly from the interior of the tire shoe or casing after the vulcanization thereof.

Another object of the invention is to form the entire core of comparatively thin sheet 20 metal as contradistinguished from the usual cast metal cores to thereby reduce the weight of the core and reduce the labor incident to the use of the ordinary form of core.

Pneumatic tire casings are usually built 25 up and vulcanized on a rigid core but it is well known that a better product can be produced by removing the core from the casing after the building up process and inserting an air bag into the cavity of the casing and 30 after placing the casing in the cavity of a two part mold inflating the air bag and vulcanizing the casing under heavy pressure.

Another object of the invention is therefore to provide a core which may be used 35 in the building up process and which may also be used to stretch the casing during vulcanization.

I accomplish the above named object by 40 forming a core of various sections each formed of two halves divided circumferentially along the periphery of the core and incorporate in each section mechanism for separating the two halves of each section laterally to thereby stretch the tire during 45 vulcanization. The operation of the mechanism for separating the two halves of the various sections being operated by the mold members during their inward movement toward each other which takes place previous 50 to the vulcanizing operation so that the mold members are moved toward each other after clamping the tire shoe about the core and within the mold. The mechanism for separating the core members is operated simultaneously with the inward movement of

the mold members. The operation of the spreading means for the core members takes place synchronously with the clamping together of the members of the mold.

With the foregoing and other objects in view the invention consists in the novel construction, combination and arrangement of parts to be hereinafter specifically described and illustrated in the accompanying drawings which form a part hereof wherein is shown the preferred embodiment of the invention, but it is to be understood that changes, variations and modifications can be resorted to which come within the scope of the matter hereinafter claimed.

In the drawings in which similar reference numerals indicate like parts in the different figures:

Figure 1 is a plan view of a core embodying the present invention.

Fig. 2 is a fragmentary view enlarged of a portion of the core shown in Fig. 1.

Fig. 3 is a similar view looking from a point within the inner circumference of said annulus.

Fig. 4 is a transverse sectional view of a mold with the core positioned therein surrounded by a tire shoe and with the spreading mechanism in its inoperative position.

Fig. 5 is a similar view to Fig. 4 with the spreading mechanism in its operative position.

Fig. 6 is a fragmentary plan view of the exterior surface of the core looking outwardly from the center of the annulus showing the spreading mechanism in the position shown in Fig. 4.

Fig. 7 is a similar view to Fig. 6 showing the spreading mechanism in the position shown in Fig. 5.

Fig. 8 is a sectional view of the spreading mechanism showing in connection therewith means for locking the two members of the core together during the building up of the tire.

Fig. 9 is a view similar to Fig. 8 with the locking mechanism in its inoperative position and the spreading mechanism in its operative position.

Fig. 10 is a perspective view of one of the holding members for the spreading mechanism.

Fig. 11 is a perspective view of a pair of the holding members that are used at the ends of each of said separable sections.

Fig. 12 is a similar view of a pair of the holding members showing means for securing said separable sections in abutment against lateral displacement.

5 Fig. 13 is a fragmental perspective view of the inwardly projecting radial flange of said core showing means of securing said sections in abutment against longitudinal displacement as the same is positioned when 10 the spreading mechanism is in its inoperative position.

Fig. 14 is a similar view showing the same with the spreading mechanism in its operative position.

15 The core which forms the subject matter of the present invention preferably consists of four separable sections, 1, 2, 3 and 4, the peripheral and lateral portions of which are fashioned to impart to the interior of the 20 tire the desired conformation. The lines of severance between the section 1 and the sections 2 and 4 are oblique to a radius of the core and the same is true of the lines of severance between the section 3 and the sections 2 and 4 so that the sides of the sections 1 and 3 are approximately wedge-shaped to permit their easy inward withdrawal from the interior of the tire-shoe or carcass. All of the sections are split circumferentially along the tread or in other 30 words each section is formed of two opposing and similar members which are arranged co-operatively to form in co-operation a segment shaped section capable of forming a 35 portion of a core which constitutes means on which a tire-shoe may be built up. In view of the fact that all of the sections are similarly formed of two opposing and complementary members, the reference numeral 40 5 is used to denote one-half of one section, for example and the numeral 6 to designate the opposing complementary section each of the members of each section is provided with inwardly extending flanges 7 so that 45 when the core sections are united the various core flanges form a continuous annulus extending inwardly from the core members and with the two flanges opposing each other and arranged in spaced relation to each 50 other. The parts are so disposed that when assembled the ends of the members 6 on one side of the core abut against similar members on the same side and the member 5 against similar members on the opposite side 55 of the core and thereby form a substantially tubular annulus, the arrangement being such that, for example, when the two complementary members forming the section 2 are united the end portions thereof will abut against 60 similar united members of the sections 1 and 3 and so on throughout the entire core.

When the spreading device is in its inoperative position as shown in Fig. 4, it will be noted that the opposing complementary 65 members 5 and 6 are overlapped along the

periphery of the core so that when the spreading mechanism is in its operative position as shown in Fig. 5, the core will still present a continuous unbroken surface to the inner face of the tire. In order to hold the 70 opposing and complementary members 5 and 6 of each section of the core together, I have provided a locking device for holding the two members in co-operation. This locking device is so fashioned that when in one position it constitutes a means for holding the opposing members of each section rigidly together and when in another position to release said members from a locked position and also to be engaged by the mold members for forcing the two members of each section away from each other for stretching the tire shoe during vulcanization. The release of the locking mechanism synchronizes with the clamping of 80 the mold members about the tire shoe mounted on the core; a combined locking and spreading mechanism is similar for all the sections. It is believed that a description of one will be sufficient for the understanding 85 of them all.

Each combined locking and spreading device comprises a pair of holding members 8 each having a curvilinearly formed head 9, the outer face of which is fashioned to fit 90 against the interior of one of the sections and be there retained by spot welding, riveting or other holding means 10 and provided with an extension 11, extending inwardly along the inner face of the flange of 100 the section in which it is positioned. Each of these holding members is provided with a recess 12 and at its outer end with a bearing 13 and along the extension 11 with a bearing 14. The bearings 13 and 14 are 105 in alinement with each other and the bearing 13 is not cylindrical but has a flattened portion as shown in Fig. 10 and the outer portion of the bearing 14 is provided at 15 with a similar bearing for a purpose to be 110 later described. The holding members 8 are positioned or arranged in pairs with a plurality of pairs in each of the sections so that the recessed portion 12 of the members 8 on one-half of the section, say 5, is oppositely disposed to the recessed portion of a similar member in the complementary half 6 of the same section, and the bearings 13 and 14 of the members 8 of the same pair in each section are in radial alinement and in 115 parallelism and constitute, when the two members 5 and 6 of the core section are united holding means or bearings for the combined locking and spreading members. Extending across, approximately radially 120 of the recesses 12 of the holding members 8, are the bars 16, spaced from the lateral wall 125 of the recess and in parallelism therewith.

As all of the combined locking and spreading members are similar, it is 130

thought that a description of one will be sufficient for the understanding of them all and the reference numeral 17 will be used generally to designate these members.

5 Each member comprises a shaft 18 preferably formed integrally with which, are a pair of spaced locking members 19 disposed in pairs and with the members of each pair disposed diametrically opposite to each other on the shaft and the pairs arranged in spaced relation as shown in Figs. 2, 4 and 5. The general contour of each member of each pair is in the form of an S-shaped hook, 19, with the outer hook portions so positioned as to engage the cross bars 16 and hook over these bars for holding the two members 8 against movement with their inner opposing faces in engagement and of course the locking together of the various 20 members 8 of the section holds the members 5 and 6 of each section against movement. When the shaft 18 is rotated in one direction the hooks 19 engage the rods 16 and when rotated in a reversed direction they 25 disengage these from the rods and free separation of the two members of each mold is permitted. The position of the hooks or locking means for the two sections is indicated by dotted lines in Fig. 8 and the locking 30 means are shown in their inoperative position in Fig. 9 with the two members 8 arranged in spaced relation. The inner portion of each of the shafts 18 are provided with a pair of oppositely disposed 35 cams, 20, preferably formed integrally with the shaft 18 and arranged to lie in the position shown in Fig. 6, when the locking members are in the position shown in Fig. 8 and lie in the position shown in Fig. 7, 40 when the locking members 20 are in the position shown in Fig. 9. The inner end of each of the shafts 18 is provided with squared portions 21 to receive the operating wrench. The outer end of each of the 45 shafts 18 is provided with flattened portion 22, as shown in Fig. 2, which is arranged to seat in the flattened bearing formed by the recesses 13 of the member 8 and is furthermore provided with a flattened portion 50 23 which is arranged to lie in the flattened bearing formed by the portions 15 of the members 8. These flattened portions are so positioned that when the members 8 are in engagement with each other and the core 55 sections are in a position for building up of a tire, these flattened portions 22 and 23 will be substantially received in the bearings formed by the recesses 13 and 15 when the locking members 19 are in the position 60 shown in Fig. 8. The partial rotation of these flattened portions serves to set up a wedging action for separating the members 8 and also the sections to which they are connected as shown in Fig. 9 thereby 65 spreading the members 5 and 6 of the core

sections for stretching the fabric of the tire-shoe. The rotation of the shafts 18 in order to lock the two halves 5 and 6 together is accomplished by applying a wrench to the squared portions 21 of these shafts and giving a partial rotation thereto which causes the hook portion 19 to engage the bars 16. The shafts are given a reverse rotation to release hooks 19 from the pins 16 by the inner portions of the mold members engaging the cams 20, as the mold members are gradually clamped toward each other about the tire carcass which causes a partial rotation of the cams 20 and the shaft 18, thereby releasing the hooks 19 and rotating the shaft 18 causing the flattened portions 22 and 23 of the shaft 18 to engage the bearings 13 and 15 forcing the two mold members 8 apart in unison with the mold members 5 and 6 and accomplishing the function of stretching the fabric. As soon as the process of vulcanization is accomplished a wrench is applied to the squared portions 21 and the various shafts are rotated to cause interengagement of the hooks 19 with the bars 16, locking the two halves 5 and 6 of each section together and then the two halves of each section are removed as a unit from the interior of a tire-shoe in the ordinary manner.

The halves 5 and 6 of each section, 1, 2, 3 and 4 are preferably constructed so that the said halves have the knife-like edges which overlap along the periphery of the core, as shown at 24, Fig. 4. The width of the overlapped surface is sufficient to permit the lateral extension of the two halves 5 and 6 without causing a break in the surface of the core, as shown at 24 in Fig. 5.

The sections 1, 2, 3 and 4 are held in abutment against longitudinal displacement by means of a ring composed of sections 25, 26, 27 and 28. The ring section 25 is attached to one of the halves of core section 1 and extends over the core sections 2 and 4 and is secured at one end to one of the halves of section 2 and at the other end to section 4 by means of bolts 29. The sections 2 and 3 are similarly united, likewise the sections 3 and 4.

The various sections of which the core is composed are held in abutment against lateral displacement by means of a tongue 30 and an accommodating groove 31, positioned on the abutting surfaces of the core sections 1, 2, 3 and 4.

While I have described and shown a means for holding the various sections in abutment against lateral and longitudinal movement it is evident that the said sections 125 may be secured in position in various ways.

It is also apparent that although I have described an adaptation of my invention wherein the two halves of the core are comprised of separable sections that for use in 130

constructing types of tires, the halves 5 and 6 could each be made in the form of two solid rings.

It is also to be understood that while I have shown and described an embodiment of my invention constructed of sheet metal having reinforcing members 8 that the members 8 may be formed integral with the walls of the core 5 and 6.

10 The core may be constructed with the abutting ends of the sections practically closed by the reinforcing members 8 as shown in Figs. 11 and 12 or the strengthening members 8 may be positioned remote from the ends of each section and each section provided with telescoping flange 31 as shown in Fig. 2.

Having thus described my invention what I claim as new and desire to secure by Letters-Patent is:—

20 1. A core of the class described comprising a plurality of separable sections adapted to abut in the form of a tubular annulus, each of said sections divided into two opposing complementary members along a circumferentially extending line conforming to a radius of the core, automatic means located within each section for laterally and parallelly separating said members when the core is placed within the cavity of a mold.

25 2. A core of the class described comprising a plurality of separable sections adapted when assembled to form a tubular annulus each of said sections divided into two opposing complementary members along a circumferentially extending line conforming to a radius of the core; each member provided with a plurality of strengthening members which extend inwardly from the inner wall 30 thereof, automatic means located within each section to releasably connect said strengthening members, said means adapted when the core is placed within a cavity of a two-part member to disconnect said members and force them laterally apart.

40 3. A core of the class described comprising a plurality of separable sections adapted to abut in the form of an annulus each of said sections divided into two members 35 along a circumferentially extending line conforming to a radius of the core, means within each section to laterally separate said members comprising a plurality of centrally positioned radially extending rotatable shafts provided with a plurality of 45 hooks adapted to secure said members in

attachment, said shafts also adapted when rotated to disengage said hooks and move said members laterally apart.

4. In combination with a tire vulcanizing mold, a tire building core divided into two annular halves and means located within said core to automatically move the halves laterally and parallelly apart when the same is placed within the cavity of said mold.

5. A tire building and stretching core comprising an annular shell having the shape of the interior of the tire, said shell formed of two halves adapted to overlap along the peripheral portions of the core, said core having mechanism incorporated therein whereby the halves may be extended laterally to increase the size of the core.

6. A tire building and stretching core comprising an annular shell having the shape of the interior of the tire, said shell formed of two halves adapted to overlap along the peripheral portions of the core, each of said halves composed of separable sections, means to hold said sections in abutment and means to laterally extend said halves.

7. A tire building and stretching core comprising an annular shell having the shape of the interior of the tire to be constructed thereon, said shell formed of two halves adapted to overlap along the peripheral portions of the core, each of said halves composed of separable sections, means to hold said sections in abutment and means to hold said halves in position during the building up of the tire and means to laterally extend said halves and enlarge the core during the vulcanization of the tire.

8. A tire building and stretching core comprising an annular shell having the shape of the interior of the tire, said shell formed of two halves adapted to overlap along the peripheral portions of the core, each of said halves composed of separable sections, means to hold said sections in abutment and means to lock said halves rigidly together during the building up of the tire, said means automatically spreading the halves laterally upon said overlapped portions thereby extending the core when the same is placed within the cavity of a tire vulcanizing mold.

In testimony whereof I have hereunto set my hand.

VICTOR L. COX.
